UNITED STATES PATENT OFFICE

ADON J. HOFFMAN, OF SYRACUSE, NEW YORK, ASSIGNOR TO WILLIAM H. HOFFMAN, OF ONEONTA, NEW YORK

GARMENT PRESSING MACHINE

Application filed March 15, 1928, Serial No. 261,987. Renewed March 4, 1932.

This invention pertains to improvements in garment pressing machines and while the invention produces a press which is of general utility it is designed more particularly for domestic work.

Hitherto garment presses have been restricted in their use mainly to factories and tailoring shops; this primarily by reason of the fact that no adequate means is available in the home for producing steam requisite to a proper pressing action.

The main object of the present invention is to provide means whereby a liquid such as water may be transformed into steam and ejected against the pressing face of one of the pressing elements for the purpose of dampening the garment to be pressed or to dampen the underlying press cloth which is forced into contact with the garment being treated.

An embodiment of the invention is shown in the annexed drawings wherein

Figure 1 is a sectional elevation of the head and buck elements of a press,

Figure 2 a longitudinal sectional view of the head with parts broken away,

Figure 3 a detail sectional view showing the water measuring chamber, two of the control valves and the conduits leading to the spray producing structure,

Figure 4 a top plan view of the head with the cover plate removed, and

Figure 5 a longitudinal vertical section of the head.

In the drawings 1 denotes a buck which may be heated as by any suitable means (not shown) and 2 the pressing face of the head. The head will, of course, be mounted upon suitable mechanism for movement toward and from the buck but as such arrangement has nothing to do with the present invention it is not shown.

The pressing face 2 of the head is formed of metal and has imposed thereon, and held in close relation thereto, suitable electrical heating elements 3 of any approved form. A flexible cable 4 extends therefrom.

The member 2 is provided, adjacent its center and extending longitudinally thereof, with a pair of upstanding ribs 5 and 6 spaced

from each other and forming with an overlying plate 7, which is secured to the member 2, a longitudinally extending chamber 8. Said member 7 also holds the inner runs of the heating element 3 in position and in close contact with the ribs 5 and 6 so that the chamber 8 is maintained in a highly heated condition at all times.

A suitable sheet or plate 9, as asbestos, overlies the outer runs of the heating element 3 and overlies the plate 7, being held in position by a plate 10, which latter is secured in place by screws 11.

A cover plate 12 extends over the entire head except the under pressing face 2 and a filler 13 of asbestos or the like underlies the cover plate and prevents radiation of heat.

The plate or member 10 is provided with a centrally disposed hub 14 through which extends a pipe 15, said pipe at its lower end terminating at the upper part of the channel 5 and having secured thereto a T fitting 16.

Secured to each of the horizontal ends of the T is a pipe 17 each pipe being provided with a series of horizontally disposed perforations 18 throughout its length. Said pipes 17, as will be seen, lie within the chamber 5 and consequently the pipe becomes heated by reason of the fact that the surrounding metal portion of the head is heated as above specified.

A slot 19 extends throughout the length of the chamber below the T 16 and the tubes 17, opening outwardly through the pressing face 2 and directly above a baffle plate 20. Said plate is formed of relatively flexible non-corrosive metal and is designed, when the head is lowered into pressing position, to be forced upwardly into a recess 21 standing directly above the plate in the pressing face 2.

The upper end of the pipe 15 is connected into a T 22 the lateral branch of which is connected with a pipe 23 which in turn is connected to a T 24, the upper opening of which latter is interconnected with a valve 25. The valve in turn is in communication through a flexible pipe 26 with a source of air under pressure.

To the upper end of the T 22 there is secured a short tubular section 27 to which in turn is secured a valve 28. Said valve is in communication with a water receiving and measuring chamber 29, water being delivered thereto through a valve 30 interconnected with a conduit 31 preferably formed of flexible material to allow for movement of the head with reference to the buck.

The water chamber 29 adjacent its upper end is connected with the air line through a check-valve 32 extending into the horizontal member of the T 24. The valve seats outwardly of the water chamber and thus prevents outflow of water therefrom while permitting air under pressure to flow inwardly when the valve 25 is open.

Mounted in the upper end of the fitting 27 is a plug or bushing 33 threaded into which is a tube or pipe 34 of relatively small diameter, said tube extending downwardly through the T 22 and the pipe 15. At its lower end it is provided with lateral branches or nozzles 35 and 36 which terminate within the tubes 17.

The under face of the pressing element 2 will preferably be planished and for certain purposes the usual wire screen, denoted by 37, and the press cloth 38 may be omitted. For the sake of clarity these latter elements are not shown in any of the figures but Figure 1.

The operation of the press is as follows: Current is turned on and the head is allowed to become thoroughly heated before any pressing operation is undertaken. When the desired heat obtains the operator will open valve 30 and allow the chamber 29 to be filled with water. He will then open the valves 25 and 28, valve 30 being closed, and air under pressure passing from the line 26 will force the water from the chamber 29 downwardly through the tube 34 and through the nozzles or laterals 35 and 36. At the same time air will pass downwardly through the pipe 23, pipe 15 and into the perforate tubes 17.

The pipe 17 being heated and the chamber 8 likewise being hot the water which is in atomized or semi-atomized condition will be converted into steam and will be forced outwardly through the slot 19 into contact with the underlying baffle 20 and thus spread outwardly over the entire pressing surface of the member 2.

If the head is held close to the garment the garment will be dampened or if the press cloth is employed said cloth will be dampened and may be brought into contact with the underlying garment on the buck. The head is then depressed and being hot will effect the proper operation through the damp pressing cloth or cover or will effect the proper pressing operation of the dampened garment if the cloth is absent.

When the pressing has been effected air alone may be admitted to the chamber 8 and blown outwardly onto the pressed garment or through the press cloth onto the garment. Such air will of course act to remove moisture from the garment, if any be present, and inasmuch as the air becomes heated in its passage through chamber 8 its drying action is enhanced.

What is claimed is:

1. In a garment pressing machine the combination of cooperative pressing elements, one of which at least as provided with a chamber having an opening terminating directly at the outer pressing face of such element substantially coextensive with the length thereof; means for heating the walls of said chamber; and means for spraying a liquid into the chamber.

2. In a garment pressing machine the combination of cooperative pressing elements, one of which at least is provided with a chamber having an opening terminating directly at the outer pressing face of such element; means for heating the walls of said chamber; means for spraying a liquid into the chamber; and means for introducing compressed air into said chamber.

3. In a garment pressing machine the combination of cooperative pressing elements, one of which at least is provided with a chamber having an opening terminating directly at the outer pressing face of such element; means for heating the walls of said chamber; and means including a source of air under compression for forcing water in a sprayed condition into said chamber.

4. In a garment pressing machine the combination of cooperative pressing elements one of which at least is provided with a chamber having an opening extending lengthwise of the pressing member and terminating directly at the outer pressing face thereof; means for heating said chamber; a perforate pipe located in said chamber; means for introducing water into said pipe; and means for introducing air under pressure into said pipe.

5. In a garment pressing machine the combination of cooperative pressing elements one of which at least is provided with a chamber having an opening terminating directly at the outer pressing face thereof; means for heating said chamber; a perforate pipe located in said chamber; means for injecting water into said pipe; and means for introducing air under pressure into said pipe.

6. In a garment pressing machine, the combination of cooperative pressing elements one of which at least is provided with a chamber having an opening terminating at the pressing face thereof; means for heating said chamber; a perforate pipe located in said chamber; means for introducing air under pressure into said pipe; means for supplying water in measured quantities to said pipe;

and means for admitting air under pressure to the water for forcing the same outwardly of the pipe.

7. In a garment pressing machine the combination of cooperative pressing elements, one of which at least is provided with a chamber having an opening terminating directly at the outer pressing face of said element; means for heating said element and chamber; means for producing steam within the chamber; and means for introducing air under pressure into the chamber.

8. In a garment pressing machine the combination of cooperative pressing elements, one of which at least is provided with a chamber having an opening terminating directly at the outer pressing face of said element; means for heating said element and chamber; means for producing steam within the chamber; means for introducing air under pressure into the chamber; and means for spreading the steam laterally as it passes from the opening.

9. In a garment pressing machine the combination of cooperative pressing elements, one of which at least is provided with a chamber having an opening terminating at the pressing face of said element; means for heating said element and chamber; a perforate tube housed in said chamber; a conduit extending upwardly therefrom; means under control of the operator for introducing compressed air into said conduit; a water receiving chamber; a tube extending therefrom and terminating within the perforate tube; and means under the control of the operator for admitting air under pressure to said water chamber.

10. In a garment press, the combination of co-operative pressing elements; a nozzle carried by one of said elements; a liquid measuring chamber connected to the nozzle; a source of air under compression likewise connected to the nozzle and opening into the liquid chamber; means under the control of the operator for admitting liquid to the measuring chamber; and means for thereafter admitting air under pressure to said chamber and the nozzle to force the liquid therefrom.

In testimony whereof I have signed my name to this specification.

ADON J. HOFFMAN.
